UNITED STATES PATENT OFFICE.

LAWRENCE G. REPELL, OF KANSAS CITY, MISSOURI.

KEY-FASTENER.

No. 907,285.

Specification of Letters Patent.

Patented Dec. 22, 1908.

Application filed November 8, 1907. Serial No. 401,297.

To all whom it may concern:

Be it known that I, LAWRENCE G. REPELL, a citizen of the United States, residing at Kansas City, in the county of Jackson and State of Missouri, have invented certain new and useful Improvements in Key-Fasteners, of which the following is a specification.

My invention relates to improvements in key fasteners.

10 The object of my invention is to provide a portable device which may be readily attached to a door for the purpose of holding a key from being turned in the lock by a person at the outer side of the door.

15 The novel features of my invention are hereinafter fully described and claimed.

In the accompanying drawings illustrating my invention—Figure 1 is an inside elevation of a portion of a door to which is affixed my improved key fastener, the fastener being shown holding the key in the locked position. Fig. 2 is an elevation taken at right angles to the view shown in Fig. 1. Fig. 3 is a view partly in vertical section and partly 20 in elevation, the front plate of the support being removed and the securing member being shown in vertical section. Fig. 4 is a 25 central vertical sectional view taken on the dotted line *a*—*b* of Fig. 3. Fig. 5 is a perspective view of the rotary member. Fig. 30 6 is a perspective view of the upper end of the bolt. Fig. 7 is a horizontal sectional view taken on the dotted line *c*—*d* of Fig. 4.

Similar characters of reference denote similar parts.

1 denotes a door and 2 an ordinary flat shank key. The support for a rotary key holding member or disk 3 is provided at its upper end with a ring like portion 4 and a 40 vertical shank 5. The support comprises preferably two vertical plates 6 and 7 secured flatwise to each other by rivets 8. The circular upper end of the plate 6 on its front side is provided with a horizontal circular recess in which is rotatively mounted the disk or rotary member 3. A vertical groove extends in the front side of the plate 6 from the said circular recess to the lower end of said plate. The rotary member 3 is 45 provided with a radial peripheral notch 9 for receiving and holding the shank of the key 2. A horizontal hole 10 is provided in each plate 6 and 7 in alignment with the central portion of the rotary member 3 to receive the 50 key shank. The ring like portion 4 of the support is provided with a transverse slot 11

adapted to register with the notch 9 when the rotary member 3 and key 2 are turned to the unlocked position, which position is diametrically opposite that shown in Figs. 60 1 and 3. The vertical groove in the forward side of the plate 6 is covered by the plate 7 and forms a longitudinal hole in which is vertically slidable a bolt or locking member 12, the upper end of which is movable in and 65 out of a recess 13 extending radially inward from one end of a peripheral groove 14 extending a portion of the circumference of the rotary member 3.

In a recess 15 in the forward side of the 70 plate 6 is mounted a vertical coil spring 16 the upper end of which bears against the lower side of the upper horizontal arm of a U shaped plate secured in a lateral recess 17 in the bolt 12, said U shaped plate being 75 denoted by 18. The lower end of the spring 16 is supported by a projection 20 extending inwardly from the outer side of the recess 15. The lower horizontal arm of the U shaped plate 18 is disposed in the 80 recess 15 below the projection 20, and limits the downward movement of the bolt 12. The spring 16 normally forces the bolt upward so that it may enter the recess 13 when the rotary member 3 is turned to the locked 85 position shown in Fig. 3. When the key 2 and rotary member 3 are turned clockwise to a position diametrically opposite that shown in Fig. 3; the bolt 12 will reach the end of the groove 14 opposite the end terminating in the recess 13, and the rotary member will be stopped by said bolt with the notch 9 in register with the slot 11 in the ring like portion 4 of the support. When the 90 rotary member is in the last named position, the key shank may be made to pass out of the notch 9 through the slot 11.

To secure the fastener to the door or other object a securing member comprising preferably a screw hook 21 is provided in its shank 100 with a longitudinal slot 22 which extends along the shank and into the curve of the hooked portion 23. The shank is provided with a screw threaded portion 24 adapted to be screwed into the door 1. The lower 105 end of the bolt 12 extends through the slot 22 and below the shank of the hook 21 has secured to it a screw 25 having a spherical head too large to pass through the slot 22. When secured to the door 1, the hook 21 has 110 its curved portion 23 turned downward so that the bolt 12 may be swung vertically to

and from a position in which the key shank, when in the lock, may be inserted into the notch 9 through the slot 11. When the key is disengaged from the fastener, the bolt and support may be swung vertically downward so as to hang from the hook 21.

In operating my invention, the securing hook 21 is first secured to the door in the proper position, the rotary member 3 being disposed with the notch 9 registering with the slot 11. The device is then affixed to the key shank by passing the shank 2 through the slot 11 into the notch 9. The key is then turned in the lock to the position shown in Figs. 1 and 3 at which time the bolt 12 will enter the recess 13 and hold the rotary member from turning, and thus preventing the key 2 from being turned by any one at the outer side of the door 1. To unlock the door from the inner side, the bolt 12 is pulled downward against the pressure of the spring 16 out of the recess 13, at which time the key may be turned to the unlocked position.

Modifications of my invention, within the scope of the appended claims, may be made without departing from its spirit.

Having thus described my invention, what I claim and desire to secure by Letters Patent is:—

1. In a key fastener, the combination with a support having a ring like portion provided with a transverse slot to receive therethrough a key, of a rotary member mounted on said support in said ring like portion and having a peripheral notch to receive and hold the key shank, said rotary member having around a portion of its circumference a peripheral groove provided at one end with a radial recess, and a locking member mounted on said support and in said groove and movable in and out of said recess when the key and rotary member has been turned to the locked position, said locking member stopping the rotation of said rotary member in the opposite direction in a position in which said slot and notch will register.

2. In a key fastener, the combination with a support having a ring like portion provided with a transverse slot to receive therethrough a key, of a rotary member mounted in said ring like portion and having a peripheral notch to receive and hold the key shank, said rotary member having around a portion of its circumference a peripheral groove provided at one end with a radial recess, and a bolt mounted in said peripheral groove and slidable on said support into and out of said recess when the key and rotary member have been turned to the locked position, said bolt serving as a stop to hold the rotary member in a position in which the said notch and slot will register.

3. In a key fastener, the combination with

a support having a ring like portion provided with a transverse slot to receive therethrough a key shank, of a rotary member mounted in said ring like portion and having a peripheral notch to receive and hold said key shank 70 against rotation when the rotary member is held from rotating, said rotary member having around a portion of its circumference a peripheral groove provided at one end with a radial recess, a bolt slidable on said support into and out of said recess when the rotary member is in the locked position, said bolt being mounted in said groove and serving as a stop to hold the rotary member in a position in which said slot and notch will 80 register, and a spring for sliding said bolt into said recess.

4. In a key fastener, the combination with a support having a ring like portion provided with a transverse slot to receive a key shank, 85 of a rotary member mounted in said ring like portion and having a peripheral notch for holding the key shank from rotating when the rotary member is held from rotating, said rotary member having a peripheral recess, a bolt slidable on said support into and out of said recess for holding the rotary member in the locked position, said bolt also serving to stop the rotation of the rotary member in a position in which the said slot and 95 notch will register, and means for sliding said bolt into said recess.

5. In a key fastener, the combination with a support having a ring like portion provided with a transverse slot for receiving a key 100 shank, of a rotary member mounted in said ring like portion and having a peripheral notch for receiving and holding a key shank, said rotary member having a peripheral recess, a bolt slidable into and out of said recess when said rotary member is turned to the locked position, the bolt also serving as a stop for holding the rotary member in a position in which said slot and notch will register, means for forcing said bolt into said recess, and means for pivotally securing said bolt to a door or other object. 110

6. In a key fastener, the combination with a hook for securing to a door, the hook having a shank provided with a longitudinal 115 slot extending into the curved portion of the hook, of a support, a rotary member mounted on said support and having means for receiving and holding a key shank, a bolt slidable on said support into and from a position 120 in which it will engage and hold the rotary member in the locked position, said bolt being pivoted in the slot in said hook so as to swing vertically, and a spring for forcing said bolt into engagement with said rotary member. 125

7. In a key fastener, the combination with a support having a ring like portion provided with a transverse slot to receive therethrough a key shank, and having a shank provided 130

with a longitudinal hole, of a rotary member mounted in said ring like portion and having a peripheral notch to receive a key shank and also a peripheral groove terminating at 5 one end in a radial recess, a bolt slideable in said longitudinal hole in the shank of said support into and out of said recess, said bolt being disposed in said peripheral groove and serving as a stop for holding the rotary member 10 in a position in which the said slot and notch will register, the bolt when in said recess holding the rotary member in the locked position with the notch out of register with

15 said slot, a spring mounted on said support for forcing the bolt into said recess, and a securing member to which the bolt is pivoted so as to swing vertically to and from a position in which the key shank may enter said slot in said support.

In testimony whereof I have signed my 20 name to this specification in presence of two subscribing witnesses.
